UNITED STATES PATENT OFFICE.

JOSEPH A. NOE, OF SHARPSBURG, PENNSYLVANIA.

DESIGN FOR A GLASS BOTTLE.

Application filed October 2, 1925. Serial No. 14,994. Term of patent 14 years.

To all whom it may concern:

Be it known that I, JOSEPH A. NOE, a citizen of the United States, residing at Sharpsburg, in the county of Allegheny and State of Pennsylvania, have invented a new, original, and ornamental Design for Glass Bottles, of which the following is a specification, reference being had to the accompanying drawing, forming part thereof.

The Figure 1 is a side view in elevation of a glass bottle showing my new design.

The Figure 2 is a sectional view at 2—2 on Figure 1.

I claim:

The ornamental design for a glass bottle, as shown.

JOSEPH A. NOE.
